UNITED STATES PATENT OFFICE.

HARRY P. BASSETT, OF CYNTHIANA, KENTUCKY, ASSIGNOR OF ONE-THIRD TO CURTIS C. MEIGS, OF PHILADELPHIA, PENNSYLVANIA, AND ONE-THIRD TO CLARENCE L. PARKER, OF WASHINGTON, DISTRICT OF COLUMBIA.

CONTINUOUS-ACTION RETORT.

1,314,849.

Specification of Letters Patent.

Patented Sept. 2, 1919.

Application filed September 17, 1918. Serial No. 254,435.

To all whom it may concern:

Be it known that I, HARRY P. BASSETT, a citizen of the United States, residing at Cynthiana, in the county of Harrison and 5 State of Kentucky, have invented certain new and useful Improvements in Continuous-Action Retorts, of which the following is a specification.

This invention relates to rotary retorts 10 wherein solids are heated either for the purpose of distillation or to subject gases or vapors to the action of solids heated therein.

Retorts of this character are subject to 15 the disadvantage that their action is not continuous. From time to time their operation must be stopped, the contents removed and the retorts recharged. Aside from the trouble and expense incident to discharging and recharging the retorts, their operation 20 must be continued at undiminished expense for heat after the maximum efficiency of the charge is past by reason of its becoming partially spent, or the contents of the retort removed while a portion of it is still adapted 25 for further treatment, thereby adding materially to the cost of the operation.

This invention is designed to overcome 30 these disadvantages by providing rotary retorts of the character referred to, with means whereby the spent contents are automatically and continuously removed and the 35 action of the retort made continuous.

Other objects and advantages of the invention will be apparent during the course 35 of the following description.

In the drawings forming a part of this specification and in which like numerals are employed to designate like parts throughout the same,

40 Figure 1 is a central vertical longitudinal sectional view through apparatus embodying my invention,

Fig. 2 is an enlarged transverse vertical sectional view taken on line 2—2 of Fig. 45 1, and,

Fig. 3 is a central vertical longitudinal sectional view through a slightly different form of apparatus.

Attention being called to Figs. 1 to 3 50 inclusive, the numeral 5 designates the heating chamber of the apparatus, which may be

formed of refractory material and arranged within a casing 6. The heating chamber 5 discharges at its lower end into a fire-box 7, having a grate 8, with an ash pit 9 there- 55 beneath. Fuel, such as coal or the like, is fed into the fire-box 7 through an opening 10 which may be covered by a suitable door (not shown). The products of combustion escape from the heating chamber 5 through 60 openings 11, arranged in the top thereof. These openings discharge into longitudinal passages 12, having communication with passages 13, leading to a stack 14.

The numeral 15 designates a horizontal 65 rotatable drum or receptacle disposed within the heating chamber 5. In each form of the invention, the drum 15 has its forward end closed by a head 16, rigidly secured therein. This head is provided near its periphery 70 with an opening 17, covered by a plate 18, secured thereto by any suitable means. A neck or tube 19 is rigidly secured to the plate 18, and preferably formed integral therewith. This tube projects through a sta- 75 tionary bearing sleeve 20, rigidly secured to the casing 6. Bearing elements or rollers 21 are carried within the sleeve 20, and serve to rotatably support the tube 19.

The tube 19 serves to rotate or drive the 80 drum 15 and has a worm wheel 22 rigidly secured thereto. This worm wheel is in- closed within a casing 23. The worm wheel 22 receives its rotation from a worm 24, in- closed within the lower portion of the casing 85 23, and driven by a shaft 25, receiving its power from any suitable source.

At its opposite or rear end, the drum 15, has a second head 26, rigidly secured therein. This head is provided centrally thereof with 90 a tube or neck 27, preferably formed integral therewith. The tube or neck 27 contacts with bearing elements or rollers 29, which are carried within a bearing sleeve 30, rigidly secured to the casing 6, as shown. 95 From the foregoing description, it is apparent that the opposite ends of the drum 15 are rotatably supported, and that means are provided to rotate the drum.

The principal feature of the invention 100 consists in the provision of means for continuously removing the spent material from

the drum 15, during its rotation, and without stopping the same. Such means comprises a circular plate 31, extending transversely within the drum 15, near and 5 slightly spaced from the head 26, providing a radially extending space 32. The plate 31 abuts against the annular flange 33 of the head 26, and an annular angle-iron 34 is preferably arranged within contact with 10 the plate 31, and is secured thereto and connected with the drum 15, thereby serving to couple the plate 31 to the drum 15 for rotation therewith. Arranged within the radical space 32 is an annular flange 35, 15 which is concentric with relation to the plate 31 and is attached thereto to rotate therewith. The plate 31 is provided at equidistantly spaced intervals with openings 36, substantially semi-circular, and having their 20 larger portions arranged substantially flush with the inner surface of the annular flange 35, as shown. The openings 36 serve to permit the spent solid material within the drum 15, which material during the continuous 25 agitation thereof caused by the rotation of the drum gravitates to the lower portion of the drum, to pass into the radial space 32. The drum 15 is rotated in the direction of the arrow in Fig. 2, and this spent solid 30 material within the space 32 is caught by curved or spiral vanes 37, rigidly attached to the plate 31. These vanes are arranged approximately radially of the plate 31, and accordingly feed the solid material to the 35 central portion of the plate. The upper or inner portions of these vanes are also transversely inclined, and diverge outwardly, thereby serving to deflect or elevate solid material into and through a stationary tubular chute 38, mounted within the rotatable 40 tube 27. This chute is secured to a stationary plate 39, in turn attached to the bearing sleeve 29. The plate 39 has an opening 40, for placing the chute 38 into communication 45 with an inclined chute 41, preferably leading to a closed or hermetically sealed chamber (not shown).

The foregoing construction is common to both modifications of the invention and I 50 will now describe the construction, embodying the feeding means, which is specific to the first form of the invention, and illustrated in Fig. 1.

Arranged within the tube 19 is a stationary member 42, having a lower inlet bore 43 and an upper outlet bore 44. At its inner end, the member 42 has a flange 45, secured thereto, slidably contacting with the inner end of the tube 19, as shown. A stationary head 46 is provided upon its inner face with an annular groove 47, slidably receiving the forward reduced end of the sleeve 19. This stationary head is secured to the member 42 by any suitable means.

The coupling 48 is connected with the member 42 and in free communication with the bore 46. Connected with the outer end of the coupling 48 is an elbow 49, having connection with a valve casing 50, connected with a hopper 51. This hopper is supported by suitable means, as shown at 52 and 53. A rotatable feed valve or star-wheel 54 is mounted within the valve casing 50 and may be driven by any suitable means to intermittently feed the solid material from the hopper 51 at any desired rate into the elbow 49. A spiral conveyer 55 operates within the bore 43, and serves to feed the solid material through this bore into the forward end of the drum 15. The spiral conveyer receives its rotation from a shaft 56, driven by a pulley 57, actuated by an suitable source of power. An elbow 58 is connected with the stationary plate 46 and has communication with the bore 44. This elbow is connected with an outlet conduit 59, having a valve 60, connected therein.

In the embodiment of my invention shown in Fig. 3, a stationary head 61 slidably engages the outer end of the sleeve 19, and this head is equipped with openings 62, 63 and 64. A conveyer conduit 65 extends through the opening 64, and fits within an opening formed in and near plate 67, slidably engaging the tube 19. A conveyer conduit 65 receives a spiral conveyer 68, carried by a shaft 69, driven by a pulley 70. The conveyer conduit 65 receives solid material from a valve casing 71, having a rotatable valve or star wheel 72 therein. The valve casing 71 is secured to the lower end of a hopper 73, suitably supported, as shown at 74 and 75.

The gas or vapor to be treated by the solid material is fed through a pipe 76, having connection with a horizontal pipe 77, extending through the opening 63 and an opening 78 in the plate 67. The pipe 77 extends centrally and longitudinally within the drum 15. The pipe 76 is equipped with a cut-off valve 79. An outlet pipe 80 is equipped with a cut-off valve 81, and is connected with a pipe 82, which extends through the openings 63 and through an opening 83 in the plate 78.

The operation of the first embodiment of my apparatus is as follows:

The solid material to be heated or distilled, such as calcium acetate is fed from the hopper 57 as intermittently and as rapidly as desired, by means of the rotatable valve 54, into the conveyer conduit and propelled forwardly by the spiral conveyer 55. This material is discharged into the drum 15, wherein it is subjected to distillation. The gases to be collected escape through the bore 44 and pass into the pipe 59, and discharge from this pipe upon opening the

valve 60. During the rotation of the drum 15, the used or spent portions of the solid material gravitate to the lower portion thereof and pass through the openings 36 into the radial space 32. This solid spent material is carried upwardly by the vanes 37 and discharges into the chute 38, from which it passes into the inclined chute 41.

The form of apparatus shown in Fig. 3 is designed for treating gases or vapors, such for example as the vapors of sulfur containing oils to the action of solid materials or reagents such for example as iron oxid, fragmentary iron bodies such as chips, or turnings, or the like, in the presence of heat. In the operation of this form of apparatus, the gases or vapors to be treated are passed into the revolving drum 15 through pipe 77. The solid material is fed from the hopper 73 into the conveyer conduit 65, by means of the rotatable valve 72. The spiral conveyer 58 feeds this material into the rotatable drum. The treated gases or vapors pass through the pipe 82 and through pipe 80, when the valve 81 is opened. The spent or used solid material, such as iron sulfid where the retort is employed in the removal of sulfur or sulfur compounds from petroleum oils, gravitates to the lower portion of the drum 15, and is removed therefrom, as indicated in connection with the first form of my apparatus.

It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus describtd my invention, I claim:

1. In apparatus of the character described, a drum provided at one end with an outlet opening near the central portion of the same, means to heat the drum, means to rotate the drum, means to feed material to the drum, and approximately radial vanes arranged within the drum near the outlet thereof and connected with the drum for rotation therewith, said vanes extending from points near the outer portion of the drum to a point near the outlet, the inner ends of the vanes being inclined laterally and diverging outwardly toward the outlet.

2. In apparatus of the character described, a drum provided at one end with an outlet opening arranged near the central portion of the same, means to heat the drum, means to turn the drum upon its longitudinal axis, means to feed material to the drum, a radial plate arranged within the drum and secured thereto and disposed near and spaced from the outlet for providing a radial discharge

passage, there being an opening or openings 65 near the periphery of the radial plate, and approximately radial vanes arranged within said passage and rotatable with the plate, said vanes extending from points near the openings to a point near the outlet. 70

3. In apparatus of the character described, an approximately horizontal drum provided at one end with an inlet opening and at its opposite end with an outlet opening, said outlet opening being disposed near the central longitudinal axis of the drum, means to heat the drum, means to rotate the drum, means to feed material through the inlet opening, a radial plate arranged within the drum near and spaced from 80 the outlet opening and secured to the drum for rotation therewith, said plate serving to provide a radial passage and having openings formed therein near its periphery, and devices disposed within the radial passage and serving to convey material from the openings of the plate to the outlet opening. 85

4. In apparatus of the character described, an approximately horizontal drum provided 90 at one end with an outlet disposed approximately centrally thereof, means to heat the drum, means to rotate the drum, means to feed material to the drum, a radial plate arranged within the drum near and spaced 95 from the outlet and secured to the drum for rotation therewith, said plate being provided with openings disposed near its periphery, and curved vanes arranged between the plate and adjacent end of the drum and adapted for rotation therewith, said vanes extending from points near the openings to a point near the outlet, and serving to conduct material from the lower portion of the drum to the outlet. 100

5. In apparatus of the character described, a drum provided at one end with an outlet arranged near the center of such end, means to heat the drum, means to rotate the drum, means to feed material to the drum, a radial plate arranged within the drum and secured thereto and disposed near and spaced from the end of the drum having the outlet for providing a discharge passage, said plate being provided near its periphery with openings, and longitudinally curved vanes arranged within said passage and rotatable with the plate, said vanes extending from points near the openings to a point near the outlet, the inner ends of the vanes being inclined laterally and converging outwardly toward the outlet. 115

6. In apparatus of the character described, a furnace embodying a casing, bearing elements arranged within the ends of the casing, a rotatable drum arranged within the casing, tubes connected with the ends of the drum and operating within the bearing ele- 120 125

4
ments, a relatively stationary inlet conduit leading through one tube, a conveyer operating within the inlet conduit, a relatively stationary outlet conduit leading through the same tube, and automatic means arranged within the drum near the other tube and adapted to convey material from the lower portion of the drum and discharge the same at a point near the last named tube.

In testimony whereof I affix my signature to
in the presence of two witnesses.

HARRY P. BASSETT.
